C. B. FOWLER

TELEPHONE EXCHANGE SYSTEM

Filed Sept. 23, 1919

Inventor:
Clarence B. Fowler.

by *J. Roberts* Att'y.

UNITED STATES PATENT OFFICE.

CLARENCE B. FOWLER, OF NEW YORK, N. Y., ASSIGNOR TO WESTERN ELECTRIC COMPANY, INCORPORATED, OF NEW YORK, N. Y., A CORPORATION OF NEW YORK.

TELEPHONE-EXCHANGE SYSTEM.

Application filed September 23, 1919. Serial No. 325,610.

To all whom it may concern:

Be it known that I, CLARENCE B. FOWLER, a citizen of the United States, residing at New York, in the county of New York, 5 State of New York, have invented certain new and useful Improvements in Telephone Exchange Systems, of which the following is a full, clear, concise, and exact description.

10 This invention relates to telephone exchange systems and more particularly to such systems in which connections between telephone lines terminating at manual and automatic exchanges are established by way 15 of trunk circuits, over which automatic switches are controlled from the manual exchange for effecting connections between the trunk circuits and telephone lines at the automatic exchange.

20 The object of this invention is the production of an improved system of this character by which the operators at the manual exchange may control automatic switches provided at the automatic exchange and in 25 which complete supervision over the connection is given to the operators at the manual exchange.

In accordance with the various features of this invention which is in the nature of an 30 improvement of that of an application of H. L. Hoffman, Serial No. 322,092, filed September 6, 1919, an operator's impulse sending device provided at the manual exchange and common to the link circuits 35 thereof, is rendered individual to a link circuit when connected with a trunk circuit extending to the automatic exchange by means responsive to the initial actuation of the impulse sending device. Means provided at 40 the manual office and controlled over the trunk circuit in turn controls the disconnection of the impulse sending device from the particular engaged link circuit, and further means under the control of the operator is 45 provided whereby, if the sending device has not been disconnected by the means controlled over the trunk circuit prior to the time that the operator desires to connect the sending device with another link circuit, the 50 operator may disconnect the sending device from the engaged link circuit. Condensers are provided in the talking conductors of the trunk circuit which normally prevent the flow of direct current from the manual to the 55 automatic exchange, and when transmitting

selecting impulses the trunk circuit beyond the condensers is intermittently opened and closed under control of a relay controlled over one of the talking conductors of the engaged link and trunk circuits by an impulse 60 sending device.

For a more complete understanding of this invention reference should be had to the following description and to the accompanying drawing which illustrates one embodiment 65 of the invention.

There is shown in the drawing a telephone line A which terminates at a manual exchange, where it may be connected with a link circuit B in any suitable and well 70 known manner. The calling end of the link circuit B may be connected with a trunk circuit C extending from the manual to an automatic exchange, at which are provided the usual selector and connector switches for 75 effecting connection between the trunk circuit and telephone lines, such as D, terminating at the automatic exchange. The apparatus shown to the left of the vertical dotted line is located at the manual exchange, and 80 that to the right of this line at the automatic exchange. The nature of this invention is such that it is believed that a clear understanding thereof will be obtained from a description of the operation of the system 85 shown in the drawing, and it will be so described.

The subscriber at the station on telephone line A having initiated a call and the answering end of the link circuit B having been 90 associated therewith in any well known manner, the operator actuates listening key 5, connecting the operator's telephone set in circuit so that the operator may converse with the calling subscriber to ascertain the 95 number of the line with which connection is desired. Assuming that connection is desired with telephone line D, which terminates at the automatic exchange, the operator inserts calling plug 6 of the link circuit B 100 into jack 7 of the trunk circuit C. Calling supervisory lamp 8 lights and sleeve relay 9 operates over a circuit from battery through the lamp 8, resistance 10, sleeve contacts of the plug 6 and the jack 7 and winding of 105 relay 9 to ground. The operation of relay 9 causes the operation of slow release relay 12 over a circuit from battery through the right-hand contact of relay 9, winding of relay 12 and normal contact of relay 13 to 110

ground. The operation of relay 12 establishes a short circuit for the windings of the polarized relay 18.

The operator may now actuate impulse sending device 15, which is common to the link circuits at the operator's position, preparatory to sending out the impulses necessary for selecting telephone line D and for effecting connection of the trunk circuit C therewith. Upon the initial actuation of the impulse sending device 15, off-normal contact 16 closes and remains closed during the entire movement of the sending device or until it returns to normal position, causing the energization of sending device connecting relay 17 over a circuit from battery through the normal contact of the polarized signal-control relay 18, ring talking conductor of the trunk circuit C, ring contacts of the jack 7 and the plug 6, ring talking conductor of link circuit B, winding of relay 17, middle-normal contact thereof, lower contact of listening key 5, off-normal contact 16 and normal contact of pilot relay 20 to ground. Relay 17 in operating opens the talking conductors of the link circuit B and establishes a locking circuit for the relay which may be traced from battery through the normal contact of polarized relay 18, ring contacts of the jack 7 and the plug 6, winding of relay 17, contact 21 thereof, contact of key 22 and the winding of pilot relay 20 to ground. Pilot relay 20 energizes over the circuit opening a contact in the original energizing circuit of relay 17 and causing the lighting of impulse sending device pilot lamp 23.

The closure of contact 24 of relay 17 connects the impulse contact of sending device 15 with the tip talking conductor of the engaged link and trunk circuits, thereby causing the operation of relay 13 over a circuit from battery through the winding of relay 13, normal contact of relay 25, tip talking conductor of the trunk circuit C, tip contacts of the jack 7 and the plug 6, tip talking conductor of the link circuit B, contact 24 of relay 17, and the impulse contact 32 of sending device 15 to ground.

Relay 13 in operating opens the circuit of slow release relay 12 which, in releasing, opens its contact, removing the short circuit from the winding of polarized relay 18. Relay 13 also closes its right-hand contact which is in the ring talking conductor of the trunk circuit extending to the automatic exchange. Impulse-responsive relay 30 now operates over a circuit from battery through the right-hand winding of this relay, right-hand normal contact of reversing relay 31, windings of polarized relay 18, right-hand contact of relay 13, left-hand normal contact of reversing relay 31, and the left-hand winding of impulse-responsive relay 30 to ground. The direction of flow of current through

the winding of polarized relay 18, however, is not such as to permit the operation of this relay. The impulse responsive relay 30 is responsive to the impulses transmitted through the opening and closing of the impulse contact 32 of the impulse sending device 15 and controls the usual motor magnets for the selector and connector switches provided at the automatic exchange for selecting the desired telephone line thereat and effecting connection of the trunk circuit with the selected line.

During the return movement of the sending device 15 to its normal position, the impulse contact 32 thereof is intermittently opened and closed to transmit the proper number of impulses. Upon the first opening of this impulse contact 32, relay 13 releases causing the deenergization of impulse responsive relay 30. Relay 13 in closing its left-hand contact causes the energization of slow release relay 12 which reestablishes the short circuit about the windings of the polarized relay 18. The purpose of this short circuit is to eliminate the resistance of the windings of this relay 18 from the circuit including the impulse relay, thereby increasing the signaling range and also preventing disturbances due to any inductive action which the presence of the relay 18 in the circuit might have. Relay 12 is slow in releasing so that it does not open its contact during the short time that relay 13 is energized upon the closure of the impulse contact 32 when transmitting the selecting impulses. It will be seen therefore that impulse responsive relay 30 follows the movement of the impulse contact 32 of the sending device 15 and controls the usual apparatus associated with the selector and connector switches.

After the sending of all of the impulses, telephone line D is selected and trunk circuit C is connected therewith by means of the switches 33 and 34. In the final return of the impulse sending device 15 from its normal position, impulse contact 32 remains closed. Consequently, relay 13 remains energized to maintain the continuity of the ring talking conductor of the trunk circuit C. The continued energization of relay 13 causes relay 12 to open its contact removing the short circuit from about the windings of the polarized signal-control relay 18. After the selecting impulses have been transmitted the operator may restore listening key 5 to normal position provided this has not already been done. The call bell at the station of telephone line D may be operated in the usual manner. The subscriber in responding to the operation of this call bell removes the receiver from the switchhook, thereby causing the energization of the reversing relay 31. This relay reverses the connection of the battery over the talk-

ing conductors of the trunk circuit, whereupon the direction of the flow of current through the windings of polarized relay 18 is such as to cause the operation thereof.

- 5 The opening of the normal contact of polarized relay 18 opens the locking circuit including the sending device connecting relay 17 and pilot relay 20, whereupon both release their armatures. The release of 10 pilot relay 20 extinguishes pilot lamp 23, while the release of relay 17 disconnects the sending device 15 from the link circuit B and reestablishes the continuity of the talking conductors of the link circuit B. The 15 closure of the alternate contact of polarized relay 18 connects relay 25, which is of high impedance to talking currents, in bridge of the talking conductors of the trunk circuit C on the manual side of condensers 34 and 20 35. Supervisory relay 36 and bridge relay 25 thereupon operate over a circuit from battery through the winding of supervisory relay 36, lower normal contact of ringing key 37, lower normal contact of relay 17, 25 ring contacts of the plug 6 and the jack 7, alternate contact of polarized relay 18, winding of relay 25, tip contacts of the jack 7 and the plug 6, upper normal contact of relay 17 and upper normal contact of ringing 30 key 37 to ground. The energization of supervisory relay 36 connects resistance 38 in parallel with the lamp 8, which is thereby extinguished. The extinguishment of this lamp is a signal to the operator that the 35 called subscriber has answered.

The relay 25 in closing its alternate contact, establishes a holding circuit for relay 13 before this latter relay is disconnected from the tip talking conductor of the trunk 40 circuit. The relays 17 and 13, which control the sending of the impulses from the manual exchange over the trunk circuit to the automatic exchange, are now disconnected from the talking circuit.

- 45 At the conclusion of the conversation the subscribers restore the receivers to the switchhooks. The restoration of the receiver to the switchhook at the station of telephone line D causes the deenergization of 50 reversing relay 31, which thereupon reverses the connection of battery with the talking conductors of the trunk circuit. Polarized relay 18 thereupon releases its armature causing the deenergization of supervisory 55 relay 36 and relay 25. The deenergization of supervisory relay 36 causes the supervisory lamp 8 to light to furnish a disconnect signal. The deenergization of relay 25 opens the circuit of and releases relay 13. 60 Relay 12 thereupon operates to establish a short circuit for the windings of polarized relay 18. Impulse responsive relay 30 at the automatic exchange remains energized. The operator upon observing the lighted condition of the supervisory lamp withdraws the

60 plug 6 from the jack 7 whereupon the apparatus associated with the calling end of the link circuit B and that associated with the trunk circuit C restores to normal position.

70 Should the operator, prior to the response of the called party, have desired to employ the sending device 15 in connection with another link circuit at that position, the actuation of key 22 causes the impulse sending device 15 to be disconnected from the link circuit B. This is brought about by the fact that the contact of key 22 is in the locking circuit including the windings of relays 20 and 17 which, upon being opened, 80 causes the release of both relays in the manner before described.

75 What is claimed is:

1. In a telephone exchange system, in combination, a trunk circuit, a link circuit 85 connected therewith, an impulse sending device, a relay for connecting the device with the link circuit, and a locking circuit for the relay including a portion of a talking conductor of the link circuit.

90 2. In a telephone exchange system, in combination, a trunk circuit, a link circuit connected therewith, an impulse sending device, and a relay energized over a portion of a talking conductor at the engaged link and 95 trunk circuits for connecting the device with the link circuit.

100 3. In a telephone exchange system, in combination, a trunk circuit, a link circuit connected therewith, an impulse sending device, a relay energized in response to the actuation of the sending device for connecting it with the link circuit, and a locking circuit for the relay including a portion of a talking conductor of the engaged link and trunk circuits.

105 4. In a telephone exchange system, in combination, a trunk circuit, a link circuit connected therewith, an impulse sending device, a relay energized in response to the actuation of the sending device for connecting it with the link circuit and a polarized signal-control relay bridged across the trunk circuit and controlled thereover for disconnecting the sending device from the link circuit.

110 5. In a telephone exchange system, in combination, a trunk circuit, a link circuit connected therewith, an impulse sending device, a relay energized in response to the actuation of the sending device for connecting it with the link circuit, a telephone line connected with the trunk circuit, and a polarized signal-control relay in the 115 trunk circuit and controlled thereover, by the telephone line for disconnecting the sending device from the link circuit.

120 6. In a telephone exchange system, in combination, a called line, a trunk circuit, a link circuit connected therewith, an im-

5 pulse sending device, means for connecting the sending device with the link circuit, and means in the trunk circuit and controlled by the called line for disconnecting the sending device from the link circuit.

10 7. In a telephone exchange system, in combination, a trunk circuit, a link circuit connected therewith, an impulse sending device, means for connecting the sending device with the link circuit, a called telephone line connected with the trunk circuit and a signal-control relay in the trunk circuit controlled thereover by the closure of the telephone line for disconnecting the sending device from the link circuit.

15 8. In a telephone exchange system, in combination, a trunk circuit comprising talking conductors, an operator's link circuit connected with the trunk circuit, an impulse sending device, an impulse responsive relay, an impedance device, permanently bridged across the talking conductors of the trunk circuit, means operated in response to the actuation of the impulse sending device for connecting it with the link circuit, means controlled by and effective during the operation of the sending device for establishing a non-inductive path around the impedance device, and means controlled by the sending device for opening and closing the circuit including the talking conductors and the non-inductive path for controlling the impulse responsive relay.

20 9. In a telephone exchange system, in combination, a trunk circuit comprising talking conductors, an operator's link circuit connected with the trunk circuit, an impulse responsive relay, a normally closed bridge of the talking conductors, an impulse sending device, means operated in response to the actuation of the impulse sending device for connecting it with the link circuit, and means controlled by the sending device for short-circuiting said bridge and for interrupting the continuity of one of the talking conductors during the operation of the sending device for controlling the impulse responsive relay.

25 10. In a telephone exchange system, in combination, a trunk circuit comprising a pair of talking conductors, a link circuit connected with the trunk circuit, a supervisory signal therein, an impulse responsive relay, a signal-control relay bridged across the talking conductors responsive to a reversal of current over said trunk circuit for controlling said signal, an impulse sending device, means operated in response to the actuation of the impulse sending device for connecting it with the link circuit, means responsive to the operation of the sending device for transmitting impulses over the trunk circuit for controlling the impulse responsive relay, and means controlled by

and rendered effective during the operation of the sending device for short-circuiting the signal-control relay.

30 11. In a telephone exchange system, in combination, a trunk circuit comprising a talking conductor including a normally open contact, a link circuit connected with the trunk circuit, a relay in the trunk circuit initially energized over a circuit including a portion of the link circuit for closing the normally open talking conductor, and means controlled over the trunk circuit for maintaining the relay in energized condition independent of its original energizing circuit.

35 12. In a telephone exchange system, in combination, a trunk circuit comprising a pair of talking conductors, a normally open contact in one of the talking conductors, a link circuit connected with the trunk circuit, an impulse sending device, an impulse responsive relay, a control relay controlled by the impulse sending device for intermittently closing the contact to control the impulse responsive relay, and means controlled over the trunk circuit for removing the control relay from the control of the sending device and for maintaining it in energized condition to close the contact.

40 13. In a telephone exchange system, a calling line, a called line, means including an operator's link circuit and a trunk circuit for establishing connection between said lines, a supervisory signal in said link circuit, a repeating relay in said trunk circuit, a bridge in said trunk circuit for controlling said signal, an impulse sender, a circuit therefor extending over one talking conductor of said link circuit and said trunk circuit for controlling said repeating relay, means operated in response to the actuation of the impulse sender for connecting the impulse sender and the control circuit, and means controlled by said repeating relay for repeating said impulses over the two sides of said trunk circuit in series and for short-circuiting said bridge during the sending of impulses.

45 14. In a telephone exchange system, a calling and a called subscriber's line, means including an operator's link circuit and a trunk circuit for interconnecting said lines, a supervisory signal in said link circuit, an impulse responsive relay, a relay bridged across the trunk circuit responsive to a reversal of current for actuating said signal, an impulse sender, means operated in response to the actuation of said impulse sender for connecting it with said link circuit, means responsive to the operation of the sending device for controlling said impulse responsive relay, and means controlled by and rendered effective during the operation of said sending device for short-circuiting said bridged relay.

15. In a telephone exchange system, a plurality of subscribers' lines, means including an operator's link circuit and a trunk circuit for establishing a connection between the calling and a called line, a repeating relay in said trunk circuit, an impulse sender, a circuit therefor extending over one talking conductor of said link circuit and said trunk circuit for controlling said repeating relay, means operated in response to the actuation of the impulse sender for connecting the impulse sender and the control circuit, condensers in the talking conductors of the trunk circuit, a supervisory signal in the link circuit, a bridge between the talking conductors of the trunk circuit and intermediate the calling line and said condensers, a relay in one of the talking conductors of the link circuit for controlling said signal, a normally open bridge between the talking conductors of the trunk circuit intermediate said condensers and the called line, a relay in said second bridge responsive to a reversal of current over said called line for closing said first mentioned bridge to operate the relay in the link circuit over the two talking conductors of the link circuit in series, and means controlled by said repeating relay for short-circuiting said second mentioned bridge during the operation of said repeating relay.

In witness whereof, I hereunto subscribe my name this 19th day of September A. D., 1919.

CLARENCE B. FOWLER.
